DESIGN FOR A VENTILATOR

Onnie Mankki, Cleveland Heights, and Francis Joseph Schultheis, Lakewood, Ohio, assignors to James B. Shaver, University Heights, Ohio

Application February 14, 1944, Serial No. 112,574

Term of patent 7 years

(Cl. D62—4)

To all whom it may concern:

Be it known that we, Onnie Mankki and Francis Joseph Schultheis, both citizens of the United States and residents of Cleveland Heights and Lakewood, respectively, in the county of Cuyahoga and State of Ohio, have invented a new, original, and ornamental Design for Ventilators, of which the following is a specification, reference being had to the accompanying drawing, forming a part thereof;

In the drawing, the figure is a perspective of a ventilator showing our new design. The other sides, not shown, are substantially like the sides shown.

We claim:

The ornamental design for a ventilator, substantially as shown and described.

ONNIE MANKKI.
FRANCIS JOSEPH SCHULTHEIS.
